UNITED STATES PATENT OFFICE.

ROBERT L. PATTERSON, OF WELLINGTON, KANSAS, ASSIGNOR OF ONE-HALF
TO HENRY A. RIEMANN, OF SAME PLACE.

MACHINE FOR DRESSING FLOORS OR THE SURFACE OF LUMBER.

SPECIFICATION forming part of Letters Patent No. 447,160, dated February 24, 1891.

Application filed March 18, 1890. Serial No. 344,343. (No model.)

To all whom it may concern:

Be it known that I, ROBERT L. PATTERSON, of Wellington, in the county of Sumner and State of Kansas, have invented a new and 5 Improved Machine for Dressing Floors or the Surface of Lumber, of which the following is a full, clear, and exact description.

My invention relates to a machine for dressing floors or the surface of lumber, and has for 10 its object to provide a light, strong, and portable machine whereby the flooring of a room or the faces or edges of lumber may be conveniently and effectively dressed with knives or with a material, such as sand-paper or 15 emery, as may be required.

The invention consists in the novel construction and combination of the several parts, as will be hereinafter fully set forth, and pointed out in the claims.

Reference is to be had to the accompanying drawings, forming a part of this specification, in which similar figures and letters of reference indicate corresponding parts in all the 20 views.

Figure 1 is a front elevation of the machine. Fig. 2 is a section on line 2 2 of Fig. 1. Fig. 3 is a transverse section through the lumber-clamping device, upon which the machine is adapted to travel. Fig. 4 is a perspective view of the said lumber-clamping device. Fig. 5 is a bottom plan view of the 25 polishing-head; and Fig. 6 is a central vertical section through the head, illustrating the application thereto of the polishing-block. Fig. 7 is a side elevation of the knife-head adapted for use in connection with the machine, showing the knives of the head in side elevation. Fig. 8 is a similar view showing the edges of the knives, and Fig. 9 is a plan 30 view of the knife-head.

The sides 10 of the machine each consists of a skeleton frame comprising two legs a , united by a suitable cross-bar a' , near their lower ends, an upper cross-bar a^2 and a cross-bar a^3 intermediate of the lower and upper cross-bars. Above the upper cross-bar a^2 an A-frame 11 is formed upon each side piece of the machine, which A-frame virtually constitutes an integral portion of the frame below

the upper cross-bar a^2 , and usually each entire side frame is cast in one piece.

The right-hand side frame 10 is provided with a downwardly-extending member 12, integral with the inner edge of the front leg between its lower extremity and its junction with the lower cross-bar a' . The member 12 constitutes, essentially, a third leg, and has journaled therein a wheel 13, preferably provided with a rubber tire 14. The rear legs of the machine and the front leg of the left-hand side frame are likewise provided with similar wheels 13, all of which wheels are adapted to travel upon the floor to be polished.

The side frames 10 are connected, preferably, by two cross-bars 15 and 16, which cross-bars are secured to the upper cross-bars a^2 of the side frames, and in the upper portion of the A-frames suitable journal-boxes are constructed, in which a drive-shaft 17 is held to turn, the said drive-shaft being provided at 20 one outer end with a crank 18, and upon the shaft between the A-frames a bevel-gear 19 is secured. The gear 19 meshes with a pinion 20, attached to a spindle 21, held to turn in the bed cross-bar 15, and upon said spindle 21, below the pinion 20, a horizontal spur-gear 22 is attached.

In the front bed cross-bar 16, the hub 23 of a pinion 24 is held to turn, the pinion being adapted to mesh with the spur-gear 22, and 25 the hub of the pinion projects downward below the cross-bar 16, and is provided with a collar 25, held in connection therewith by a set-screw or equivalent fastening device. By means of the said collar the pinion and its hub 23 are held in proper position.

The pinion, and likewise the hub, is provided with a central bore having a feather formed therein, which feather is adapted to enter a longitudinal groove 26, formed in the upper end of a perpendicular shaft 27, which shaft is passed through the bore of the pinion and is rotated by the drive-shaft 17 through the medium of the intermediate gear above described. The lower end of the shaft is projected downward through a suitable bore in a front horizontal platform 28, which platform connects with the front legs of the side frames

10. It may here be remarked that the rear portions of the side frames are usually connected by brace-bars 29, which preferably partake of the form of the letter X, as shown in 5 Fig. 1.

Upon the shaft 27, preferably above its central portion, a sleeve 30 is secured, preferably by means of a set-screw, which sleeve is provided with a recess 31 in its upper face, and 10 above the fixed sleeve 30 a second sleeve 32 is loosely mounted upon the shaft, the under face of which is provided with a recess facing with and corresponding to the recess 31 of the lower sleeve, and between the two sleeves 15 a spring 33 is coiled around the shaft, having a seat in the recessed surfaces of the sleeves, as best illustrated in Fig. 2.

From the front edge of the front bed cross-bar 16 a post 34 is downwardly projected, 20 upon which post a lever 35 is centrally fulcrumed, provided with a bifurcated outer end adapted to receive the shaft 27 and rest upon the upper surface of the loosely-mounted sleeve 32.

25 To the inner end of the lever 35 a rod 36 is pivotally connected, the upper end of which rod is threaded and projected upward through an aperture in the said front cross-bar 16. The rod is threaded to receive a hand-wheel 30 or thumb-nut 37, whereby when the rod 36 is drawn upward by the manipulation of the thumb-nut 37 the bifurcated end of the lever is made to press the loose sleeve 32 downward against the spring 33, and as the shaft 35 27 is capable of vertical movement, a proper degree of tension may be exerted upon the shaft, and a suitable cushion formed therefor, to permit of a polishing or knife head, hereinafter described, and which is attached 40 to the lower end of the shaft, shaping itself to the undulating surface of a floor, for instance. The downward movement of the shaft 27 is controlled by a collar 38, adjustably secured thereto, which collar has a bearing 45 against the upper face of the platform, and the upward movement of the shaft is regulated by the upper face of the sleeve-section of the polishing or knife head contacting with the under face of the platform. The

50 polishing-head A is shown in detail in Figs. 5 and 6, and as attached to the shaft in Figs. 1 and 2, and the said head consists of a disk-like body 39, having a sleeve-extension 40, integral with its upper central portion, a downwardly-extending marginal flange 41, and lugs 42, integral with its under face, one being 55 preferably placed at each side of a central bore 43, vertically produced in the body and sleeve to receive the lower end of the shaft 27, which lower end of the shaft is threaded, as best shown in Fig. 6.

In connection with the head A a block 44 is employed, having recesses formed in its upper face to receive the lugs 42 of the head, 60 whereby it is prevented from turning upon the head when attached thereto, and the said

block is also provided at its center with a conical opening 45, extending through from bottom to top. The lower threaded end of the shaft 27 extends downward through this 70 opening, and a washer 46 is introduced upon the shaft to a contact with the walls of the opening 45, and is firmly attached to the head through the medium of a nut 47, screwed upon the extremity of the shaft to an engagement 75 with the washer. It will be observed that the peripheral surface of the block is flared outward, whereby, when the emery-paper or sand-paper or solid emery or sandstone is secured to the block, which may be done in any 80 approved manner, the corners of the floor or the edges thereof may be readily reached.

The polishing-head is substituted when occasion may demand by a knife-head B. (Illustrated in detail in Figs. 7, 8, and 9.) The 85 knife-head is somewhat conical in general outline, being provided with a flat under face and a central bore 48, which bore is increased in diameter at the under face of the head, as illustrated in dotted lines at 49 in Fig. 7, and 90 in the opposite sides of the head vertical recesses 50 are produced, which recesses are made at the periphery, and the upper face of the head in front of one wall of each recess is beveled downward or rendered somewhat spiral, as indicated at 51 in Figs. 7 and 8. The exposed walls of the recesses 50 face in opposite directions, as may be readily observed by reference to Fig. 7, and to the exposed wall of each recess 50 a knife 52 is secured, 95 essentially L-shaped, the attachment being made at the vertical member by means of a screw 53 or its equivalent, and the horizontal member, the edge of which constitutes the cutting-edge of the knife, is carried below 100 the under face of the head. Thus the cutting-edges of the knives also face in opposite directions, one following substantially in the track of the other when the head is revolved. It will also be noticed that the knives are so 105 set in their recesses as to extend slightly beyond the periphery of the head. This is done to accomplish the same purpose sought to be obtained by beveling the block of the polishing-head. 115

When a floor is to be trued up, for instance, or the inequalities removed, the knife-head is placed upon the shaft and is revolved as the machine is advanced by means of the crank 18 and the gear-connection between 120 the drive-shaft and the perpendicular shaft 27. When the floor is to be polished only, or the inequalities are very slight, the polishing-head containing the emery or sand paper is substituted for the knife-head. 125

In order that the machine may be used to true the faces or edges of boards, slats, or any kind of lumber, the machine is provided upon the inner face of each leg of the left-hand side frame with a grooved wheel 54, the 130 said grooved wheel being so journaled that it will not contact with the floor when the de-

vice is used upon the same; but when lumber is to be operated upon the frame D is used. (Shown in detail in Fig. 4, and in cross-section, Fig. 3.) This frame is rectangular, being braced by suitable transverse bolts 55, and upon the top of one side bar of the frame a track 56 is longitudinally laid.

The side bars of the frame are both provided with a series of transverse apertures 57 for the reception of rods 58, which pass through both side bars and are adapted to support the lumber 59 to be dressed, and also act as a guide. The lumber to be dressed is supported upon the rods 58, and the surface to be removed is that above the plane of the upper face of the side bar next to which the lumber is clamped by suitable clamp-rods 60, provided with a thread to be screwed into the side bar of the frame containing the track, and provided at their outer ends with a crank-arm 61, whereby they may be readily manipulated. The operation of these clamp-rods is clearly shown in Figs. 3 and 4.

To dress the lumber, the machine is placed upon the frame, the grooved wheels 54 made to travel upon the track 56, and the cushioned wheels upon the upper surface of said side bars. The operation of the machine in this connection is clearly set forth in Fig. 3, and needs no further description.

Instead of journaling the grooved wheels 54 to the inner side of the legs, as shown, the journals therefor may be dispensed with and said grooved wheels be substituted for several of the roller-wheels 13.

Having thus described my invention, I claim as new and desire to secure by Letters Patent—

1. The combination, with the wheeled frame having a vertical shaft provided at its lower end with a dressing-head, of a clamping-frame having a longitudinal track or way on its upper side, on which the said frame travels to bring the said head along the material to be dressed.

2. In a machine of the character described, the oblong frame D, having series of apertures 57 in its opposite sides, rods 58, adjustable in said apertures according to the

width of the boards to be dressed, and transverse screws projecting through one side of the frame to clamp the boards resting on said rods against the inner face of the opposite side of the frame, substantially as set forth.

3. In a machine of the character described, the dressing-head B, having a flat lower face, oppositely-facing vertical shoulder-forming recesses 50 in the edge or periphery of the head, the upper face of the head in front of each recess being beveled downward, as shown at 51, and angle-knives 52, the vertical members of which are secured to said vertical shoulders, as at 53, and the horizontal members projecting forwardly under the lower face of the head, substantially as set forth.

4. In a machine of the character described, the combination, with a frame, a drive-shaft journaled in said frame, a spur-gear provided with an attached hub, and a feather in the bore of said hub and wheel, and a binding-collar attached to the hub, of a perpendicular shaft having a longitudinal groove in its upper portion and adapted to receive the feather of the spur-gear and its hub, a spring tension device attached to the shaft, a lever fulcrumed upon the frame and having a bearing upon said device, a cutting-head secured to the lower end of the shaft, and a connection, substantially as shown and described, between the hub spur-gear and the drive-shaft, as and for the purpose specified.

5. The combination, with a machine provided with a rotary spring-pressed shaft, a cutting-head secured to the said shaft and having rollers journaled in the legs at one side of the machine and grooved wheels journaled in the legs upon the other side of the machine, of a frame provided with a track adapted to receive the grooved wheels, supporting gage-rods detachably secured in said frame, and threaded clamping-rods passed through one side bar of the frame, substantially as and for the purpose specified.

ROBERT L. PATTERSON.
